ACTION LOCK FOR SELF-LOADING FIREARMS

Paul A. Klocker, New Haven, Conn., assignor of one-half to The High Standard Manufacturing Corporation, Hamden, Conn., a corporation of Connecticut, and one-half to Sears, Roebuck and Co., Chicago, Ill., a corporation of Illinois

Application March 16, 1951, Serial No. 216,068

9 Claims. (Cl. 42—17)

1

The present invention relates in general to firearms and more especially to improvements in an action-lock for a repeating firearm of the tubular magazine type.

An object of the invention is to provide a repeating firearm with superior means for automatically locking the breech-bolt in its retired position after the discharge of the last cartridge.

A further object of the invention is to provide a repeating firearm of the tubular magazine type with superior means for automatically locking the breech-bolt in its retired position after the discharge of the last cartridge, and manually-operated means associated with the automatic locking-means for releasing the breech-bolt.

A still further object of the invention is to provide a repeating firearm of the tubular magazine type in which the cartridge-carrier serves to releasably hold the breech-bolt in its retired position after the discharge of the last cartridge.

A still further object of the invention is to provide a repeating firearm of the tubular magazine type in which the pivotal movement of the cartridge-carrier following the discharge of the last cartridge is such as to elevate the carrier into the path of the breech-bolt and simultaneously to be releasably engaged by a carrier-latch, whereby the breech-bolt is held in its retired position.

A still further object of the invention is to provide a repeating firearm of the tubular magazine type having superior carrier-latch means for automatically locking the breech-bolt in its retired position after the discharge of the last cartridge, the superior latch-means being located in a position such that it may be conveniently operated without changing one's hold on the trigger-guard portion of the firearm.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a vertical elevation in section and partly in side elevation of a repeating firearm of the tubular magazine type in which the present invention is incorporated, the breech-bolt being shown in its retired position and the carrier supporting the last cartridge in position for chambering;

Fig. 2 is a view corresponding to Fig. 1 but with the breech-bolt in its forward breech-closing position and the last cartridge chambered in the barrel;

2

Fig. 3 is a view corresponding to Figs. 1 and 2 but showing the breech-bolt moved forwardly from its retired position and releasably held from closing by engagement with the cartridge-carrier which is held up in the path of the breech-bolt by the carrier-latch means of this invention;

Fig. 4 is a transverse section of the receiver on line 4—4 of Fig. 3;

Fig. 5 is a broken top plan view of the trigger-plate of the firearm; and

Fig. 6 is a perspective view of the carrier-latch.

The particular firearm shown in the drawings for the purpose of illustrating one embodiment of the invention is a repeating firearm of the 15 slide-action type such as illustrated and described more fully in the co-pending application of Frederick L. Humeston, Ser. No. 49,313, filed September 15, 1948, patented May 8, 1951, as Patent No. 2,552,429, and comprises, in the main, a receiver 10 having a barrel 11 secured in the forward end thereof. A buttstock 12 is secured to the rear end of the receiver by fastening-means indicated at 13. A substantially rectangular recess is formed vertically in the underside of the receiver to provide an action-chamber 14 which is coaxial with the cartridge-chamber 15 of the barrel 11, the lower portion of the action-chamber 14 being adapted to accommodate the trigger-plate 16 of the firearm. In this connection, the assembled receiver 10 and trigger-plate 16 are hereinafter referred to as the "frame" of the firearm.

30 A breech-bolt 17 is movably mounted in the action-chamber 14 and supported for reciprocable movement therein on the upper edges of the trigger-plate 16. As is customary in guns of this type, a cartridge-ejection port (not shown) is provided in the right-hand side wall of the receiver, while the underside of the top wall thereof is provided with a longitudinal protuberance 14' adjacent its forward end, and at its rear end with a breech-bolt locking-notch 18 for releasably locking the breech-bolt in its forward breech-closing position as illustrated in Fig. 3. 40 A longitudinal clearance recess 17' is provided in the top of the breech-bolt 17 to accommodate the protuberance 14' when the breech-bolt is in breech-closing position, as shown in Fig. 2.

Secured to the underside of the barrel is a 50 tubular magazine, indicated generally at 19, which, as shown in Figs. 1, 2 and 3, makes a friction fit at its rear end in a counterbored aperture in the front wall of the receiver 10. The tubular magazine 19 is of approved construction common to repeating firearms of this type and includes an inner tube 20 in which is

housed a spring 21 adapted to urge a cartridge-follower 22 rearwardly in the magazine for automatically feeding cartridges from the tubular magazine to the cartridge-carrier hereinafter described.

The breech-bolt 17 is adapted to be reciprocated manually in the action-chamber 14 of the frame by means of slide mechanism including an action-slide bar, a fragmentary portion of which is shown at 23, the latter being guided for reciprocable movement in the receiver and provided at its rear end with a laterally-offset cam-lug 24 adapted to cammingly engage in a cam-recess 25 in the lower left-hand edge of the breech-bolt. Forward and rearward movements of the action-slide bar 23 impart similar movements to the breech-bolt both for moving the latter forwardly into breech-closing position and elevating its rear end up into locking engagement with the locking-notch 18 of the receiver; and for withdrawing the rear end of the breech-bolt from the locking-notch and moving the breech-bolt rearwardly in the receiver for extracting and ejecting a fired shell and automatically actuating the cartridge-carrier so as to elevate a fresh cartridge into position for chambering by the breech-bolt on its return movement into breech-closing position.

As shown in Fig. 1, the breech-bolt is provided with a vertical aperture 26 which extends longitudinally of the underside of the breech-bolt and provides clearance adjacent the rear end thereof for the fire-control mechanism which includes a spring-actuated hammer 27 pivotally mounted in the trigger-plate 16 and actuated by a trigger 28. The forward portion of the longitudinal clearance-aperture 26 at the bolt is formed with a central longitudinal rib 29 which depends from the top wall of the clearance-aperture and has a downwardly-and-rearwardly-sloping cam-surface 30 at its rear end for actuating the cartridge-carrier indicated by the numeral 32.

The magazine-throat for successively feeding cartridges from the open rear end of the tubular magazine onto the cartridge-carrier for movement thereby into the path of the breech-bolt is indicated generally at 31 and comprises two laterally-separable substantially-complementary throat-members between which the cartridge-carrier 32 is supported by a pivot-pin 33 for pivotal movement in a substantially-vertical plane beneath the underside of the breech-bolt. The cartridge-carrier is a blade-like member, as shown especially well in Figs. 4 and 5, pivoted by the aforesaid pivot-pin 33 between opposite sides of the frame and comprising a rearwardly-extending reach 34 provided with an upwardly-projecting breech-bolt engaging-lug 35.

In accordance with the objects of the invention, the rear edge 36 of the breech-bolt engaging-lug 35 comprises a downwardly-and-forwardly curved cam surface which is intersected by a transverse latch-notch 37 which constitutes one element of the improved cartridge-carrier latch-means of this invention for releasably holding the breech-bolt open after the last cartridge in the tubular magazine has been fired. The forwardly-extending reach 38 of the cartridge-carrier is provided with a curved front edge 39 which constitutes a cartridge-cutoff, while formed on the upper edge of the forward reach 38 of the cartridge-carrier immediately forwardly of its pivot-pin 33 is an upwardly-projecting breech-bolt engaging-lug 40. The underside of the cartridge-carrier 32 has an underslung belly portion which is engaged by the upper forwardly-extend-

ing substantially U-shaped reach 41 of a carrier-spring which is secured at its rear end by a pin 42 in the vertical recess of the trigger-plate and has a lower forwardly-extending reach 43 adapted to engage against the bottom of the aforesaid recess of the trigger-plate, whereby the upper reach 41 of the spring exerts a constant force on the underside of the cartridge-carrier forwardly of its pivot-pin 33 to elevate the forwardly-extending reach 38 thereof upwardly in the magazine-throat 31.

In accordance with this construction, as the breech-bolt is moved forwardly from its retracted position shown in Fig. 1, into its breech-closing position as shown in Fig. 2, the cam-surface 30 of its rib 29 will engage the upstanding lug 40 of the cartridge-carrier, thereby pivoting the carrier downwardly in the magazine-throat 31 against the resistance of the carrier-spring arm 41. When the breech-bolt is in its forward breech-closing position as shown in Fig. 2, engagement of the heel 44 of the breech-bolt rib 29 with the upper edge of the upstanding lug 40 of the cartridge-carrier holds the forward end of the latter downwardly in a position to receive a cartridge thereon from the tubular magazine. Upon moving the breech-bolt rearwardly, its heel 44 rides off of the lug 40 of the cartridge-carrier, whereupon the latter is freed and the force of the compressed carrier-spring arm 41 serves to pivot the carrier upwardly in the magazine-throat, thereby elevating a cartridge therein upwardly into a position immediately in front of the front face of the breech-bolt, for chambering thereby. For clarity the position of the carrier when supporting a cartridge in position for chambering is hereinafter referred to as the "chambering position" of the carrier. With the cartridge supported by the carrier in this manner, the upwardly-projecting lip 45 of the forward extremity of the reach 38 of the cartridge-carrier serves to hold the nose of the cartridge against the underside of the projection 14' of the top wall of the receiver, which engagement prevents further upward pivotal movement of the cartridge-carrier. On the other hand, should there be no cartridge supported on the cartridge-carrier, then the carrier will be free to pivot upwardly to a position above its chambering position such as shown in Fig. 3, which position is hereinafter referred to as its "action-locking position," wherein its lip 45 is in the path of movement of the forward end of the breech-bolt.

The latch-means for locking the carrier in its action-locking position comprises, in addition to the aforesaid latch-notch 37 at the rear end of the pivoted carrier, a manually-operated latch indicated generally at 46. The latter is formed of substantially-flat relatively-narrow metal stock of sufficient thickness to be a substantially-rigid structure and as shown especially well in Fig. 6, is substantially U-shaped, having a substantially-flat bridge-portion 47 provided at its opposite ends with depending legs 48 and 49, respectively, projecting substantially perpendicularly from the bridge-portion 47, the leg 49 being longer than the oppositely-disposed leg 48 of the latch and of greater width to provide a finger-engaging portion 50 at its lower end for manipulating the latch in the manner hereinafter described. To this end, the bottom edge of the finger-engaging portion 50 of the latch may be serrated as indicated at 51. The legs 48 and 49, respectively, of the latch are provided with axially-aligned apertures extending transversely therethrough 75 for accommodating a pivot-pin 52 which, as

shown especially well in Fig. 4, serves to pivotally support the latch in a clearance-recess 53 of the trigger-plate, with the leg 49 of the latch in engagement with the inner surface of the left-hand wall of the receiver, and projecting downwardly through a vertical slot 54 in the trigger-plate, the mounting of the latch and the length of its arm 49 being such that the serrated edge 51 of the finger-engaging portion of the latch projects below the underside of the trigger-plate of the firearm, as shown especially well in Figs. 3 and 4. A latch-spring 55 is mounted in the clearance-recess 53 of the trigger-plate rearwardly of the latch and is arranged to constantly urge the latch into position for engagement with the latch-notch 37 of the cartridge-carrier. In particular, the latch-spring 55 comprises a coil secured in the aforesaid clearance-recess 53 of the trigger-plate by a pin extending transversely through the coil; and reaches 57 and 58, respectively, extending in opposite directions from the coil, the reach 57 extending forwardly to engage against the bridge-portion 47 of the latch and the reach 58 extending rearwardly in engagement with the bottom of the clearance-recess of the trigger-plate. In accordance with this construction, the bridge-portion 47 of the latch is biased to engage against the curved rear edge 36 of the carrier which is moved vertically relative to the latch-bridge by the action of the breech-bolt and carrier-spring. As noted particularly well in Figs. 4 and 5, the forwardly-extending reach 57 of the spring 55 engages the bridge-portion 47 of the latch to the left of the cartridge-elevator so as not to interfere with the entry of the bridge-portion 47 of the latch into the latch-notch 37 in the rear edge of the carrier.

In the normal operation of the firearm, a cartridge will be supported on the upper edge of the forwardly-extending reach 38 of the cartridge-carrier in a position for engagement by the forwardly-moving breech-bolt, the upwardly-projecting lip 45 of the carrier serving to bring the nose of the cartridge into engagement with the underside of the projection 14 of the top wall of the receiver. The cartridge thus serves to limit further upward movement of the forward end of the cartridge-carrier, whereby the rearwardly-projecting reach 34 of the cartridge-carrier is held in a relatively-elevated position with respect to the latch 46, that is to say, the latch-notch 37 in the rear edge of the rearwardly-extending reach 34 of the cartridge-carrier is disposed above the bridge-portion 47 of the latch.

The operation of the carrier-latch for holding the breech-bolt in its partially retired position, after the last cartridge has been fired as shown in Fig. 3, is as follows. Assuming that the last cartridge in the magazine has been inserted in the chamber 13 of the barrel 11 by the breech-bolt and fired, then, with the breech-bolt in its closed position, the cartridge-carrier 32 will be held down by the heel 44 of the breech-bolt opposite the open rear end of the tubular magazine. Since there are no cartridges in the magazine, no cartridge will be fed onto the carrier. Now by pulling rearwardly on the action-slide bar 23 so as to disengage the breech-bolt from the locking-notch 18 of the receiver, the subsequent rearward movement of the breech-bolt will extract the fired cartridge from the chamber of the barrel and eject the fired cartridge from the ejection-port in the side of the receiver. During the rearward excursion of the breech-bolt 17, the lug 40 of

the carrier is released by the rearwardly-moving heel 44 of the bolt, whereupon the force of the resilient reach 41 of the carrier-spring swings the forward end of the carrier upwardly, and since there is no cartridge thereon to be brought into engagement with the underside of the projection 14 of the top wall of the receiver, the carrier is free to swing upwardly beyond its aforesaid chambering position. Consequently, the rearwardly-extending reach 34 of the carrier swings downwardly below its normal position, with respect to the carrier latch, with the result that the latch-notch 37 in the rear edge of the carrier is brought opposite the bridge-portion 47 of the latch, whereupon the force of the latch-spring swings the bridge-portion 47 of the latch into the latch-notch 37 of the carrier. The carrier is thus automatically locked against pivotal movement, with the lip 45 at its forward end held up in the path of the breech-bolt. Hence, if the breech-bolt is moved forwardly in expectation of loading another cartridge into the chamber of the barrel, the forward end of the breech-bolt is brought into engagement with the upstanding lip 45 of the cartridge-elevator and positively held thereby from moving forwardly into breech-closing position. Thus, the shooter is notified automatically that there are no more cartridges in the magazine. Should the shooter wish to release the breech-bolt to move the latter into its breech-closing position, it is only necessary to manually engage the lower serrated edge of the latch-operating leg 59 to pivot the latter in a clockwise direction, as seen in Fig. 3, whereby the bridge-portion 47 of the latch is withdrawn from the latch-notch 37 of the carrier. The latter is thus unlocked and will be readily cammed down out of the path of the breech-bolt by engagement of the front face of the breech-bolt with the upstanding lip 45 of the carrier. If, on the other hand, the shooter wished to load another cartridge into the chamber of the barrel, he could do so while the breech-bolt is held in its retired position by the locked carrier, and thereafter release the carrier by manual actuation of the carrier-latch 46 to permit the breech-bolt to move forwardly and chamber the fresh cartridge. As the unlatched carrier is swung downwardly by the camming action of the forwardly-moving breech-bolt, the notch in the rear edge of the carrier is again moved to a position above the bridge-portion 47 of the latch, the bridge-portion of the latter again engaging resiliently against the lower curved edge 36 of the rearwardly-extending reach 34 of the carrier until such time as the carrier is again permitted to swing upwardly beyond its normal cartridge-chambering position.

From the foregoing description, it will be seen that the invention is characterized by the use of a pivoted cartridge-carrier in conjunction with carrier-latch means for positively holding the carrier in the path of movement of the breech-bolt to hold the latter in its retired position in the receiver when the last cartridge in the magazine has been fired; and that the carrier-latch means is of relatively simple, durable and dependable construction located conveniently for manipulation by the shooter's fingers without releasing his hold on the trigger-guard portion of the firearm. Although the cartridge-carrier latch-means is illustrated by its application to a repeating firearm having a manually-operated action-slide for opening and closing the breech-bolt, it will be understood that it is within the

purview of the invention to use the cartridge-carrier latch-means in an autoloading firearm of the blow-back type.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A repeating firearm having a frame and a barrel provided with a cartridge-chamber, and including in combination: a breech-bolt movable longitudinally in the frame of said firearm for chambering a cartridge in the cartridge-chamber of said barrel; a cartridge-magazine; a movable cartridge-carrier for transferring cartridges from the said magazine into a position for chambering by said breech-bolt, said cartridge-carrier having a chambering position and an action-locking position, a portion of said carrier being engageable with the said breech-bolt to hold the same in its retired position when the carrier is in its action-locking position; and latch-means comprising a member arranged to be releasably engageable with said cartridge carrier to lock the said breech-bolt engaging-portion thereof up in the path of movement of the breech-bolt to hold the latter from moving forwardly into breech-closing position.

2. A repeating firearm having a frame and a barrel provided with a cartridge-chamber, and including in combination: a breech-bolt movable longitudinally in the frame of said firearm for chambering a cartridge in the cartridge-chamber of said barrel; a cartridge-magazine; a movable cartridge-carrier for transferring cartridges from the said magazine into a position for chambering by said breech-bolt, said cartridge-carrier having a chambering position and an action-locking position, a portion of said carrier being engageable with the said breech-bolt to hold the same in its retired position when the carrier is in its action-locking position; and latch-means comprising a member arranged to be releasably engageable with the rear extremity of said cartridge-carrier to lock the said breech-bolt engaging-portion thereof up in the path of movement of the breech-bolt to hold the latter from moving forwardly into breech-closing position, the said member having a manually-engageable portion arranged to project from the underside of said frame for releasing the latch-member from engagement with the carrier.

3. A repeating firearm having a frame and a barrel provided with a cartridge-chamber, and including in combination: a breech-bolt movable longitudinally in the frame of said firearm for chambering a cartridge in the cartridge-chamber of said barrel; a cartridge-magazine; a movable cartridge-carrier for transferring cartridges from the said magazine into a position for chambering by said breech-bolt, said cartridge-carrier having a chambering position and an action-locking position, a portion of said carrier being engageable with the said breech-bolt to hold the same in its retired position when the carrier is in its action-locking position; latch-means comprising a member arranged to be releasably engageable with the rear extremity of said cartridge-carrier to lock the said breech-bolt engaging-portion thereof up in the path of movement of the

breech-bolt to hold the latter from moving forwardly into breech-closing position; and resilient means in engagement with the latch-member to constantly urge the latch-member into position for engagement with the rear extremity of said cartridge-carrier.

4. A repeating firearm having a frame and a barrel provided with a cartridge-chamber, and including in combination: a breech-bolt movable longitudinally in the frame of said firearm for chambering a cartridge in the cartridge-chamber of the barrel; a cartridge-magazine; a movable cartridge-carrier for transferring cartridges from the said magazine into a position for chambering by said breech-bolt, said cartridge-carrier having a chambering position and an action-locking position, a portion of said carrier being engageable with said breech-bolt to hold the same in its retired position when the said carrier is in its action-locking position and including a rearwardly-extending reach; and latch-means comprising a notch in the rear edge of the rearwardly-extending reach of said carrier and a notch-engaging member arranged to releasably engage in said notch to lock the breech-bolt engaging-portion of the carrier up in the path of movement of the breech-bolt to hold the said breech-bolt from moving forwardly into breech-closing position, said notch-engaging member having a manually-engageable portion arranged to project from the underside of the frame of said firearm for releasing the latch-engaging member from engagement with the notch in the rear edge of the rearwardly-extending reach of said carrier.

5. A repeating firearm having a frame and a barrel provided with a cartridge-chamber, and including in combination: a breech-bolt movable longitudinally in the frame of said firearm for chambering a cartridge in the cartridge-chamber of the barrel; a cartridge-magazine; a movable cartridge-carrier for transferring cartridges from the said magazine into a position for chambering by said breech-bolt, said cartridge-carrier having a chambering position and an action-locking position, a portion of said carrier being engageable with the said breech-bolt to hold the same in its retired position when the said carrier is in its action-locking position and including a rearwardly-extending reach; latch-means comprising a notch in the rear edge of the rearwardly-extending reach of said carrier and a notch-engaging member arranged to releasably engage in said notch to lock the breech-bolt engaging-portion of the carrier up in the path of movement of the breech-bolt to hold the said breech-bolt from moving forwardly into breech-closing position, said notch-engaging member having a manually-engageable portion arranged to project from the underside of the frame of said firearm for releasing the latch-engaging member from engagement with the notch in the rear edge of the rearwardly-extending reach of said carrier and a notch-engaging member arranged to releasably engage in said notch to lock the breech-bolt engaging-portion of the carrier up in the path of movement of the breech-bolt to hold the said breech-bolt from moving forwardly into breech-closing position, said notch-engaging member having a manually-engageable portion arranged to project from the underside of the frame of said firearm for releasing the latch-engaging member from engagement with the notch in the rear edge of the rearwardly-extending reach of said carrier; and resilient means mounted in said frame in engagement with said latch-engaging member to constantly urge said latch-engaging member into contact with the rear edge of the rearwardly-extending reach of said carrier for engagement with the notch therein.

6. A repeating firearm having a frame and a barrel provided with a cartridge-chamber, and including in combination: a breech-bolt movable longitudinally in the frame of said firearm for chambering a cartridge in the cartridge-chamber of the barrel; a cartridge-magazine; a movable

cartridge-carrier for transferring cartridges from the said magazine into a position for chambering by said breech-bolt, said cartridge-carrier having a chambering position and an action-locking position; a lip on the forward end of said carrier engageable with the said breech-bolt to hold the same in its retired position when the said carrier is in its action-locking position; a rearwardly-extending reach in said carrier; latch-means comprising a transverse notch in the rear edge of the rearwardly-extending reach of said carrier and an inverted substantially U-shaped notch-engaging member arranged to releasably engage in said notch to lock the breech-bolt engaging-portion of the carrier up in the path of movement of the breech-bolt to hold the said breech-bolt from moving forwardly into breech-closing position; pivotal-means arranged to pivotally support said notch-engaging member in the frame of said firearm, said notch-engaging member having a manually-engageable portion extending downwardly from one leg thereof and arranged to project from the underside of the frame for releasing the notch-engaging member from engagement with the notch of the carrier; and a spring supported in the frame rearwardly of the notch-engaging member and arranged to engage against the latter at a point thereon above its pivotal means to urge the notch-engaging member forwardly constantly into engagement with the rear edge of the rearwardly-extending reach of the cartridge-carrier for engagement in the notch thereof.

7. A repeating firearm having a frame and a barrel provided with a cartridge-chamber, and including in combination: a reciprocable breech-bolt for chambering a cartridge in the cartridge-chamber of the barrel; a tubular magazine; a pivotal cartridge-carrier for transferring cartridges from the said tubular magazine into a position for chambering by said breech-bolt, said pivotal cartridge-carrier having a chambering position and an action-locking position; a forwardly-extending reach on said carrier provided with a breech-bolt engaging-portion for holding the breech-bolt in a retired position when the carrier is in its action-locking position, the said forwardly-extending reach of said cartridge-carrier and its breech-bolt engaging-portion being adapted when said carrier is in its chambering position to elevate a cartridge from said magazine into the path of movement of the breech-bolt for chambering thereby on the forward movement of the breech-bolt, the elevation of the cartridge by the carrier being such as to bring a cartridge into engagement with the underside of the top wall of the frame, thereby preventing pivotal movement of the carrier into its action-locking position; and latch-means comprising a member releasably engageable with the rear extremity of the pivotal carrier when the latter is in its action-locking position, to lock the breech-bolt engaging-portion of the carrier in the path of movement of the breech-bolt to hold the latter from moving forwardly into breech-closing position.

8. A repeating firearm having a frame and a barrel provided with a cartridge-chamber, and including in combination: a reciprocable breech-bolt for chambering a cartridge in the cartridge-chamber of the barrel; a tubular magazine; a pivotal cartridge-carrier for transferring cartridges from the said tubular magazine into a position for chambering by said breech-bolt, said pivotal cartridge-carrier having a chambering po-

sition and an action-locking position; a forwardly-extending reach on said carrier provided with a breech-bolt engaging-portion for holding the breech-bolt in a retired position when the carrier is in its action-locking position, the said forwardly-extending reach of said cartridge-carrier and its breech-bolt engaging-portion being adapted when said carrier is in its chambering position to elevate a cartridge from said magazine into the path of movement of the breech-bolt for chambering thereby on the forward movement of the breech-bolt, the elevation of the cartridge by the carrier being such as to bring a cartridge into engagement with the underside of the top wall of the frame, thereby preventing pivotal movement of the carrier into its action-locking position; latch-means comprising a member releasably engageable with the rear extremity of the pivotal carrier when the latter is in its action-locking position, to lock the breech-bolt engaging-portion of the carrier in the path of movement of the breech-bolt to hold the latter from moving forwardly into breech-closing position; resilient means mounted on said frame to actuate said pivotal carrier; and a second resilient means arranged to hold said latch-member in engagement with the rear extremity of said pivotal carrier.

9. A repeating firearm having a frame and a barrel provided with a cartridge-chamber, and including in combination: a reciprocable breech-bolt for chambering a cartridge in the cartridge-chamber of the barrel; a tubular magazine; a pivotal cartridge-carrier for transferring cartridges from the said tubular magazine into a position for chambering by said breech-bolt, said pivotal cartridge-carrier having a chambering position and an action-locking position; a forwardly-extending reach on said carrier provided with a breech-bolt engaging-portion for holding the breech-bolt in a retired position when the carrier is in its action-locking position, the said forwardly-extending reach of said cartridge-carrier and its breech-bolt engaging-portion being adapted when said carrier is in its chambering position to elevate a cartridge from said magazine into the path of movement of the breech-bolt for chambering thereby on the forward movement of the breech-bolt, the elevation of the cartridge by the carrier being such as to bring a cartridge into engagement with the underside of a projection on the top wall of the frame, thereby preventing pivotal movement of the carrier into its action-locking position; latch-means comprising a member releasably engageable with the rear extremity of the pivotal carrier when the latter is in its action-locking position, to lock the breech-bolt engaging-portion of the carrier in the path of movement of the breech-bolt to hold the latter from moving forwardly into breech-closing position; resilient means mounted on said frame to actuate said pivotal carrier; and a second resilient means arranged to hold said latch-member in engagement with the rear extremity of said pivotal carrier, said latch-member having a manually-engageable portion arranged to project from the underside of said frame for releasing said latch-member from engagement with the rear extremity of said carrier.
